UNITED STATES PATENT OFFICE.

JAMES A. MALONEY AND FRANZ BURGER, OF WASHINGTON, D. C., ASSIGNORS
TO THE AMERICAN ELECTROPHORE COMPANY, OF SAME PLACE.

AUTOMATIC CIRCUIT-BREAKER FOR SECONDARY BATTERIES.

SPECIFICATION forming part of Letters Patent No. 252,004, dated January 3, 1882.

Application filed September 19, 1881. (No model.)

To all whom it may concern:

Be it known that we, JAMES A. MALONEY and FRANZ BURGER, of the city of Washington, in the District of Columbia, have invented 5 a new and useful Improvement in Automatic Circuit-Breakers for Secondary Batteries; and we do hereby declare the following to be a full, clear, and exact description of the same, when taken in connection with the accompanying 10 drawing and the letters of reference marked thereon.

In the drawing we have shown our improvement in circuit with an electrophore light and dynamo-electric machine, the light being on a 15 branch circuit from the electrophore.

A represents a stationary magnet having the armature B, made in the usual manner, and provided with the shaft b, resting in its bearing h, and provided on its outer end with the 20 bevel-gear l, meshing with gear l' on the shaft l, extending up onto the frame G. Within the frame G is placed the ball H, pivoted to the two arms i i, the lower end of one arm being pivoted to the head k on the upper end of 25 the shaft l, and the loose end of the other arm working in a socket, k', in the top of the frame G, as shown in the drawing. The lower end of the shaft l is at the proper time in contact with one end of a metallic spring, which is insulated at the point of contact with the shaft. 30 The other end of the spring is in metallic connection with the main-line wire, completing the circuit between the dynamo and electrophore, &c.

35 To enable others skilled in the art to make and use our invention, we will proceed to describe its operation.

When the dynamo is running the ball H, by reason of the centrifugal force imparted to it, 40 tends to be displaced from a central line or position within the frame G. This allows the shaft l to be drawn upward, thus relieving the pressure upon that part of the spring m designed

to be in contact therewith. Consequently 45 that part of the spring nearest the connection m' is in metallic contact therewith, and the circuit from the dynamo is completed through the electrophore K and light. Now, when the dynamo ceases to run, the ball H, through its connections, seeks a central line or position in 50 the frame G, the shaft l drops down and presses upon the spring m, breaks the contact at m', and the circuit is broken between the electrophore and dynamo. Consequently the electrophore completes its circuit through the light 55 alone, and any possibility of a short circuit from the electrophore through the dynamo is prevented.

Having described our invention, what we claim as new, and desire to secure by Letters 60 Patent, is—

1. An automatic circuit-breaker consisting of the ball H, with its arms i i, and the shaft l, provided with the bevel-gear l', in combination with the shaft of the armature B of the 65 electric generator, and spring m and electric circuit, all constructed and operated substantially as and for the purpose set forth.

2. In combination with an electrophore or secondary battery and dynamo-electric generator, with their circuits, a governor or regulator operated by the direct motion of said generator, in combination with the spring m, substantially as and for the purpose set forth. 70

3. In combination with a dynamo-electric 75 generator and electrophore or secondary battery, a governor or regulator consisting of the ball H, within a frame, G, and its connections with shaft l, spring m, and contact-point m', substantially as described, and for the purpose 80 set forth.

JAMES A. MALONEY.
FRANZ BURGER.
